UNITED STATES PATENT OFFICE.

CHARLES C. WILSON AND GEORGE BROWNLIE, OF ALLEGHENY,
PENNSYLVANIA.

DESIGN FOR A LETTER OR BILL FILE.

SPECIFICATION forming part of Design No. 31,671, dated October 17, 1899.

Application filed September 26, 1899. Serial No. 731,771. Term of patent 14 years.

To all whom it may concern:

Be it known that we, CHARLES C. WILSON and GEORGE BROWNLIE, citizens of the United States of America, residing at Allegheny, in the county of Allegheny and State of Pennsylvania, have invented a certain new and useful Design for Letter or Bill Files, of which the following is a specification, reference being had therein to the accompanying drawing.

10 This invention relates to a certain new and original design for letter and bill files.

In the accompanying drawing we have shown a perspective view of our original design, and, as shown in the drawing, the leading feature of the invention consists in the cylindrical stem or rod 1, with the substantially triangular-shaped spear mounted on its upper end, the longer edges of the spear 2 being beveled and the stem or rod reduced in 20 thickness for a short distance below the spear, with this reduced portion 3 terminating at its

lower end in an inclined shoulder 4. The stem or rod is centrally and rigidly mounted upon a four-legged pedestal or base 5, having the radially-extending ridges 6 arranged on its dome, with the raised edges 7 around the legs and the relief-work 8 on the latter, and the substantially semicircular-shaped scrolls 9, connecting the raised edges 7 of the legs.

Having described our invention, what we claim as new, and desire to secure by Letters Patent, is—

The design for a letter and bill file, as herein shown and described.

In testimony whereof we affix our signatures in the presence of two witnesses.

CHAS. C. WILSON.
GEORGE BROWNLIE.
